UNITED STATES PATENT OFFICE.

ALFRED HUBERT ROY FEDDEN AND LEONARD FREDERICK GEORGE BUTLER, OF
BRISTOL, ENGLAND, ASSIGNEES OF ONE-THIRD TO THE COSMOS ENGINEERING
COMPANY LIMITED, OF BRISTOL, ENGLAND.

CYLINDER FOR LIGHT ENGINES.

1,360,909

Specification of Letters Patent. Patented Nov. 30, 1920.

Application filed June 2, 1920. Serial No. 385,958.

To all whom it may concern:

Be it known that we, ALFRED HUBERT ROY FEDDEN and LEONARD FREDERICK GEORGE BUTLER, both subjects of the King 5 of England, and both residing at Bristol, England, have invented certain new and useful Improvements in Cylinders for Light Engines, of which the following is a specification.

10 This invention relates to an improved construction of cylinder and head for a light engine such for example as an internal-combustion engine. It has for its object to provide means whereby a cast-on head may be 15 more securely held to the parts on to which it is cast.

The invention is particularly suitable in its application to an air-cooled cylinder of which the cast-on head is formed of a metal 20 of high heat conductivity, such for example as aluminium.

According to the invention, a cylinder-head is cast on to a part (for example a cylinder or a valve-seating) and is characterized 25 by the said part having a flanged peripheral rib, for example a rib of T-shaped cross-section, interrupted or otherwise, which rib is carried on a surface of the part which is covered by the casting.

30 The invention also includes a cylinder or a valve-seating having a flanged peripheral rib, interrupted or otherwise, to be embraced by and interlocked with a cast-on head.

35 According to one modification of the invention the flanged rib is formed with one or more orifices to facilitate the escape of air when the head is being cast on.

One embodiment of the invention will 40 now be described with reference to the accompanying drawings, in which—

Figure 1 is a longitudinal section on the line 1—1, of Fig. 2, and

Fig. 2 is a plan of Fig. 1.

45 In the embodiment of the invention illustrated, a cylinder A provided with cooling-fins A¹ has its upper end a portion A² free from cooling-fins but having a peripheral rib B formed integral with it.

50 This rib extends outwardly from the portion A², is of T-section as shown and is preferably turned from the solid. At intervals around the rib B are orifices B¹ in the web thereof. Valve-seatings C are also

formed with ribs C¹ similar to the ribs B 55 and the ribs C¹ have orifices C² at intervals around them in a similar manner to the ribs B. A head D of material having good thermal conductivity, preferably aluminum, is cast on to the cylinder A and 60 valve-seatings C so that the metal of the head covers or embraces the ribs B and C¹ and interlocks with them. The orifices B¹ and C² permit of the escape of air from the channels formed by the ribs when the head 65 is being cast on.

The said T-section rib may extend entirely around the periphery of the cylinder or valve seating or other part of which it is formed, or it may be divided into sections 70 separated by gaps of any desired length.

An advantage of the present construction is that in addition to the ribs B and C¹ constituting a means whereby a cast-on head is retained in firm contact with the parts on 75 to which it is cast, the head is freed from encumbrance of any form of retaining device, such as studs or bolts.

Also a considerable latitude as to the position of the sparking plug is possible, and 80 if it is inserted through the side of the head, as it would be in a cylinder of the type illustrated in the accompanying drawings, there is no necessity to boss up the metal as there is adequate thickness already 85 provided in the head. The machining is thereby facilitated.

Although one particular form of the invention has been described in detail, the invention is not limited to those details and it 90 will be readily understood that the invention is applicable to an engine of the sleeve-valve type in which separate valve-seats are not required.

Moreover, the invention is not limited to 95 internal-combustion engines but is applicable to any cases where a cast-on head is desired.

What we claim as our invention and desire to secure by Letters Patent is:— 100

1. In an engine-cylinder, the combination of a part having a flanged peripheral rib, and a cylinder-head cast on said part and interlocking with said rib.

2. In an engine-cylinder, the combination 105 of a part having an interrupted flanged peripheral rib, and a cylinder head cast on said part and interlocking with the said rib.

3. In an engine-cylinder, the combination of a part having a perforated flanged peripheral rib, and a cylinder head cast on said part and interlocking with said rib.
  4. In an engine-cylinder the combination of a part having a sectionalized and perforated flanged peripheral rib, and a cylinder-head cast on said part and interlocking with said rib.
  10. 5. In an engine-cylinder, the combination of a cylinder-barrel having at one of its ends a flanged peripheral rib, and a cylinder-head cast on said barrel and interlocking with said rib.
  15. 6. In an engine-cylinder, the combination of a cylinder-barrel, having at one of its ends a sectionalized and perforated flanged peripheral rib and a cylinder-head cast on said part and interlocking with said rib.
  20. 7. In an engine-cylinder, the combination of a cylinder-barrel having at one of its ends a flanged peripheral rib, a valve-seating hav-
- ing a flanged peripheral rib, and a cylinder-head cast on to said barrel, and on to said valve-seating, and interlocking with the 25 said ribs on them.
8. In an internal-combustion engine cylinder, the combination of a cylinder barrel having radiating fins on its curved surface and a circumferential rib of T-section perforated in its web, near one end of said barrel, a valve-seating having a circumferential rib of T-section perforated in its web, and a cylinder-head cast on to said barrel and said valve-seating and interlock- 30 35 ing with the said T-section-ribs thereon.

In testimony whereof we have signed our names to this specification in the presence of two subscribing witnesses.

ALFRED HUBERT ROY FEDDEN.

LEONARD FREDERICK GEORGE BUTLER.
